UNITED STATES PATENT OFFICE.

EZRA BURT OLSON, OF CROSS FORK, PENNSYLVANIA.

SAW-HANDLE.

No. 836,456.

Specification of Letters Patent.

Patented Nov. 20, 1906.

Application filed March 7, 1906. Serial No. 304,751.

To all whom it may concern:

Be it known that I, EZRA BURT OLSON, a citizen of the United States, residing at Cross Fork, in the county of Potter and State of Pennsylvania, have invented a new and useful Saw-Handle, of which the following is a specification.

This invention relates to saw-handles, more particularly to the detachable handles of crosscut-saws, and has for its object to improve the construction and increase the utility and efficiency of devices of this class.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

In the drawings, Figure 1 is a sectional elevation. Fig. 2 is a side elevation. Fig. 3 is a perspective view of the saw-engaging clip and its threaded head and the clamp-washer in position thereon.

The improved device comprises a ferrule 10, internally threaded at one end and with the wood handle 11 connected to the other end. Engaging the threaded portion of the ferrule is a threaded plug 12, having a central aperture 13, enlarged slightly at one end. Fitting in the aperture in the plug is a saw-engaging clip 14, having a longitudinal slot 15, in which the saw 16 is supported. The clip is riveted at one end at 17 in the inner enlarged end of the aperture in the plug 12 and a wedge-key 18 forced into the portion of the slot 15 within the plug and expanding the material of the clip into the enlarged outer end of the aperture, and thereby firmly securing the clip into the plug. Slidably disposed upon the clip 14 is a clamp washer or plate 19, having a shoulder 20 extending into the free end of the ferrule, the latter being unthreaded for a short distance to provide a bearing for the shoulder, as shown. The clamp-washer thus bears both upon the

ferrule 10 and upon the adjacent edge of the saw 16, and by rotating the ferrule in one direction the plug 12, carrying the clip 14 with it, firmly clamps the saw against the washer and the washer against the ferrule, as will be obvious. The shoulder 20, bearing within the ferrule, serves as a lateral brace to support the clip centrally of the ferrule and prevent displacement between the parts. The sides of the clip 14 are distended, as at 21, to prevent the washer passing from the clip when the saw is detached.

The manner of constructing and connecting the clip 14 and the threaded plug 12 is an important feature of the invention and materially cheapens the construction and enables a broken or worn part to be replaced without the necessity for discarding the whole device.

The device is simple in construction, is strong and durable, can be inexpensively manufactured, and is readily applicable to different sizes of saws.

Having thus described the invention, what is claimed is—

1. In a device of the class described, a ferrule internally threaded, a threaded plug engaging said ferrule and with a central aperture enlarged at one end, a slotted member riveted at one end in said aperture, a wedge-key forced into the slot where it enters the aperture at the inner end of the same, and a washer slidable upon said slotted member and provided with a shoulder projecting into said ferrule and bearing between the ferrule and the saw held in said slot.

2. In a device of the class described, a ferrule internally threaded, a threaded plug engaging said ferrule and with a central aperture enlarged at one end, a slotted member riveted at one end in said aperture, a wedge-key forced into the slot where it enters the aperture at the inner end of the same, and a washer slidable upon said slotted member and bearing between said ferrule and saw.

In testimony that I claim the foregoing as my own I have hereto affixed my signature in the presence of two witnesses.

EZRA BURT OLSON.
